[57] CLAIM

The ornamental design for a pouch for carrying jewelry or similar articles, as shown and described.

DESCRIPTION

FIG. 1 is a top perspective view of a pouch for carrying jewelry or similar articles showing our new design;

FIG. 2 is a bottom perspective view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a plan of the interior of the pouch in the unfolded condition;

FIG. 8 is a plan view of the exterior of the pouch in the unfolded condition;

FIG. 9 is a front edge elevational view of FIG. 8;

FIG. 10 is a right edge elevational view thereof;

FIG. 11 is a left edge elevational view thereof;

FIG. 12 is a rear edge elevational view thereof;

FIG. 13 is a plan view of a modified form of the interior of the pouch shown in FIG. 7; and

FIG. 14 is a perspective view of the exterior of the modified form.
